UNITED STATES PATENT OFFICE.

THADDEUS S. LEES, OF AVALON, PENNSYLVANIA, ASSIGNOR OF ONE-HALF TO
FREDERICK T. ASCHMAN, OF BEAVER, PENNSYLVANIA.

FUEL-BURNER CONSTRUCTION.

1,262,067.

Specification of Letters Patent. Patented Apr. 9, 1918.

Application filed March 7, 1917. Serial No. 153,176.

To all whom it may concern:

Be it known that I, THADDEUS S. LEES, a citizen of the United States, residing at Avalon, in the county of Allegheny and 5 State of Pennsylvania, have invented certain new and useful Improvements in Fuel-Burner Constructions, of which the following is a specification.

My invention relates to an improvement 10 in fuel burner apparatus for either gaseous or solid fuel, and refers particularly to means for inducing a copious supply or current of air, in connection with the fuel being burned, whereby to facilitate or increase the combustion.

The invention consists, generally stated, in providing a conduit communicating with the atmosphere at one end and with a flue, chimney, stack, or other conduit for the 20 products of combustion at the other end, whereby to set up a current of air therethrough, and so combined or associated with the fuel burner, grate bars, or other fuel supporting or containing element as to effect 25 a positive inflow of a portion of the induced current of atmospheric air, whereby to combine with the fuel a material addition to the ordinary supply of atmospheric air.

Ordinarily, in the combustion of gaseous 30 or other fuel, it is customary to introduce the fuel to the combustion chamber and to admit the necessary air thereto by ordinary draft of the fuel in combustion, or as in the case of gas, as induced by the injection action of the gas itself.

In my invention I effect a positive air supply by deflecting a portion of a positively induced current, thus producing an air pressure as the air enters the mixer or combustion 40 chamber equal to or in excess of the pressure of the gas itself.

The material advantage in so doing is that all of the gas is utilized, effecting complete combustion and resulting economy and a 45 maximum heat per unit of fuel used.

Certain preferred arrangements or adaptations of the invention are illustrated in the accompanying drawings, in which:

Figure 1 is a view of the invention in sectional elevation, as applied to an ordinary gas heating stove.

Fig. 2 is a similar view in sectional elevation indicated by the broken line II, II, of Fig. 1.

Fig. 3 is a sectional detail view illustrat-

ing a modified construction of the mixer chamber.

Fig. 4 is a view in sectional elevation of a conventional boiler setting and furnace equipped with the invention.

60

Referring to the drawings, 2 represents the casing or frame of an ordinary gas heating stove provided with an outlet flue 3 leading into a chimney or other flue conduit 4 for carrying off the products of combustion. Such conduit is ordinarily of sufficient height to effect a draft upwardly, as in any ordinary chimney construction. It is connected with the interior of the stove 2 by the conduit 5 which as shown, is open 70 at its front end and provided with a damper as indicated at 6, for entrance of the gaseous products of combustion resulting from the burning of the gas in the grate or other corresponding element 7.

75

Grate 7 may be of any conventional form and is provided with a centrally arranged gas conduit or pipe 8, open at its lower end for introduction of gas and air as is commonly the practice with the usual "mixer". 80 Gas is supplied thereto by a terminal jet pipe 9 leading from a supply pipe 10 having the usual controlling valve 11, mounted in any suitable way to adapt it to the construction or design of the stove or its base.

85

Surrounding the conduit 8 is a shell or coping 12, preferably flaring at the bottom portion as shown, and spaced outwardly from the central conduit 8, whereby to provide for a copious supply of inwardly flowing air as indicated by the arrows.

90

Upwardly beyond the outer portion of the shell 12, which is preferably somewhat contracted around the central tube with an intervening air circulation space or spaces 95 13, is a conduit or conduits 14, leading upwardly and into the flue conduit 5. In the arrangement shown in Figs. 1 and 2, I have shown two such conduits 14 arranged in curved form at each side of the grate and leading into the flue conduit. As will be observed these conduits may be arranged in various ornamental formation or design to give a pleasing and ornamental effect.

100

In operation, ignition of the fuel emerging upwardly through the grate results in the heated products of combustion passing upwardly through the interior of the stove and by opening in damper 6 and conduits 5 and 3 to the flue 4, thereby creating a nor-

110

mal draft of usual strength. By this means an induced flow of air is effected through conduit or conduits 14, correspondingly inducing an inflow of atmospheric air at considerable velocity through the bottom and into the interior of shell 12. A portion of such air passes into the interior of conduit 8, especially as induced by the diminishing upper portion of the shell, in the manner of an injector, carrying with it the fuel gas and becoming thoroughly mixed therewith in passing to the grate. The air current may be regulated by partly closing the bottom of shell 12 or by manipulating the valve of damper 6, by its stem 15, or by setting damper valve 16 of conduit 3, such control of the products of combustion correspondingly effecting the air supply current.

In Fig. 3 I show the same general construction of mixing chamber as above described and similarly indicated by corresponding numerals, but provided with a supplemental inner shell 17 leading inwardly toward the bottom of pipe 8 with intervening spaces 18^b whereby to directly lead the air toward the central bottom inlet opening of the air conduit and thus increase the tendency of the air, or much of it, to pass therethrough.

In Fig. 4 I show an ordinary furnace construction for use with solid fuel, as coal, which is burnt in the ordinary way in the furnace chamber 7^a over the usual grate bars. In such case a conduit 14^a leads upwardly to any desired point and is connected with the flue 4^a whereby to induce a flow of air in the manner above described. The lower end of conduit 14^a is provided with an air inlet terminal 12^a, and a supplemental pipe 8^a is provided, the inlet end of which is directed downwardly into the central portion of the air inlet current location of conduit 14^a, the other end of the pipe leading upwardly by one or more terminals to a point immediately below the grate bars for delivery of air thereto.

By this means the customary draft of the furnace induces a flow of air through the furnace chamber, facilitating the combustion of the fuel and practically effecting a forced draft.

The invention is in direct contrast with any of the usual forced draft furnaces or furnace constructions heretofore used, utilizing suction fans, exhaust steam, or the like, in that it induces an independent air circulation, at an increased pressure over atmospheric pressure, and a portion of which current is deflected directly into the fuel combustion chamber under such increased pressure, by the effect of the normal draft itself.

The advantages of the invention will be readily appreciated by all those familiar with the combustion of fuel, either for do-

mestic or industrial uses or purposes. It increases the efficiency of the fuel because of the more perfect combustion, with a corresponding economy and regularity. It provides for an ample air supply by means of the indirect connection with the flue itself, thus eliminating the necessity of any positive draft-producing mechanism. It greatly augments the ordinary pressure of the fuel, when gas is used, thus overcoming any of the disadvantages of low or insufficient pressure. It provides an ample outlet for the waste products or by-products of combustion without in any way injuriously affecting the desired results or reducing or exhausting the heat, because of the accurate control of the draft so as to prevent excessive outflow of the products of combustion.

The invention may be variously utilized or adapted to different conditions of use or may be changed or modified in construction or design or otherwise by the skilled mechanic, but all such changes or modifications are to be considered as within the scope of the following claims.

What I claim is:

1. A fuel combustion apparatus, comprising a combustion chamber and a burner therein, an outlet flue, an air circulation conduit having an enlarged air inlet terminal opening to the atmosphere below the combustion chamber and connected with the flue above said chamber, and an air supply conduit for the combustion chamber having an intake terminal extending downwardly into the enlarged terminal of the air circulation conduit and a delivery terminal extending upwardly toward the combustion chamber.

2. A fuel combustion apparatus comprising a combustion chamber and a burner therein, a flue for products of combustion, an air circulation conduit having a downwardly turned inlet opening below the burner and communicating with the flue at a higher level, and an air supply conduit for the burner having a downwardly disposed intake conduit located within said circulation conduit and leading upwardly to the burner.

3. A fuel combustion apparatus comprising a combustion chamber and a burner therein, a flue for products of combustion, an air circulation conduit having a downwardly turned enlarged inlet opening below the burner and connected with the flue at a higher level, and an air supply conduit for the burner having a downwardly disposed intake conduit located within said enlarged inlet opening and leading upwardly to the burner.

4. A fuel combustion apparatus comprising a combustion chamber and a burner therein, an outlet flue, a gas and air conduit leading upwardly to said burner and having an open downwardly disposed lower

end, a gas supply jet pipe leading into said gas and air conduit and an air inlet shell surrounding the lower end of said conduit and having a pair of laterally offset portions extending upwardly and leading into a flue terminal having an inlet opening for products of combustion.

5. A fuel combustion apparatus comprising a combustion chamber and a burner 10 therein, an outlet flue, a gas and air conduit connected with said burner extending downwardly and having an open lower end, a gas supply pipe leading thereinto, and an open bottom shell surrounding the open 15 bottom of said conduit and provided with a lateral air circulation conduit extending upwardly and having a flue terminal, said shell having an inwardly deflected supplemental shell for directing incoming air to 20 the inlet of the fuel conduit.

6. A fuel combustion apparatus comprising a combustion chamber, a burner chamber, a fuel burner therein, a flue for carrying off the products of combustion from the 25 burner chamber, an air circulation conduit having its upper end connected with the flue above the burner chamber and its lower end enlarged to facilitate entrance of atmospheric air, and an air conduit for the burner 30 chamber leading upwardly thereto and hav-

ing a lower terminal located within the enlarged lower end of the air circulation conduit.

7. A fuel combustion apparatus comprising a combustion chamber, an outlet flue, 35 an air circulation conduit having a terminal opening to the atmosphere below the combustion chamber and connected with the flue above said chamber, an air supply conduit for the combustion chamber having its inlet 40 terminal extending within said air circulation conduit and opening against the flow of air therein, said air supply conduit having its outlet adjacent the point of combustion.

8. A fuel combustion apparatus comprising a combustion chamber, an outlet flue, an air circulation conduit having an enlarged inlet terminal opening to the atmosphere below the combustion chamber and connected with the flue above said chamber, and 45 an air supply conduit for the combustion chamber having its inlet terminal centrally spaced and extending within said air circulation conduit and opening against the flow of air therein, said air supply conduit having its outlet at the point of combustion.

In testimony whereof I hereunto affix my signature.

THADDEUS S. LEESE.
